US00D955156S

(12) **United States Design Patent** (10) Patent No.: **US D955,156 S**
 Amitai et al. (45) Date of Patent: ** Jun. 21, 2022

(54) **HERB DRIER**

(71) Applicants: **Asaf Amitai**, Kibutz Hatzor (IL); **Israel Goshen**, Kfar HaNagid (IL); **Rene Bracha**, Kfar HaNagid (IL)

(72) Inventors: **Asaf Amitai**, Kibutz Hatzor (IL); **Israel Goshen**, Kfar HaNagid (IL)

(73) Assignees: **Asaf Amitai**, Kibutz Hatzor (IL); **Israel Goshen**, Kfar Hanagid (IL); **Rene Bracha**, Kfar Hanagid (IL)

(**) Term: **15 Years**

(21) Appl. No.: **29/713,772**

(22) Filed: **Nov. 19, 2019**

(51) LOC (13) Cl. **07-99**

(52) U.S. Cl.

USPC **D7/368**; D7/415; D15/10

(58) **Field of Classification Search**

USPC D7/412, 368, 601, 607, 608, 701; D3/229, 237, 252; D15/10, 17, 28, 144

CPC .. F26B 19/005; F26B 3/06; F26B 3/02; F26B 2200/06; F29B 9/103

(57) **CLAIM**

The ornamental design for a herb drier, as shown and described.

DESCRIPTION

FIG. 1 is an isometric view of the herb drier showing our new design;

FIG. 2 is an exploded isometric view thereof;

FIG. 3 is a front view thereof;

FIG. 4 is back view thereof;

FIG. 5 is a top view thereof;

FIG. 6 is a bottom view thereof;

FIG. 7 is a left side view thereof;

FIG. 8 is a right side view thereof;

FIG. 9 is another front view thereof showing open compartments; and,

FIG. 10 is another top view thereof showing a configuration where a top flap is open.

The broken lines in the drawings show environmental structure that forms no part of the claimed design.

1 Claim, 9 Drawing Sheets
